Pierre Barnes
ATTORNEY.

UNITED STATES PATENT OFFICE.

JOHN H. CORNALL, OF SEATTLE, WASHINGTON.

AUTOMOBILE-LOCKING DEVICE.

1,258,630.

Specification of Letters Patent.

Patented Mar. 5, 1918.

Application filed September 24, 1917. Serial No. 193,022.

To all whom it may concern:

Be it known that I, JOHN H. CORNALL, a citizen of the United States, residing at Seattle, in the county of King and State of Washington, have invented certain new and useful improvements in Automobile-Locking Devices, of which the following is a specification.

This invention relates to locks for automobiles, and its object is to provide a simple and inexpensively constructed lock arranged to be permanently secured to an automobile and adapted to be readily employed by the driver to effectually secure one of the car's controlling devices so as to prevent the car from being driven away by an unauthorized person.

The invention consists in the novel construction, adaptation and combination of devices as will be hereinafter described and claimed.

In the accompanying drawings, Figure 1 is a plan view of my improved lock with the cover omitted and shown partly in section. Fig. 2 is a longitudinal vertical section of the lock. Fig. 3 is a plan view of the same. Fig. 4 is a sectional view through 4—4 of Fig. 2. Fig. 5 is a plan view of one of the lock disks; and Fig. 6 is an edge view thereof. Fig. 7 is a plan view of the other lock disk and Fig. 8 is an edge view of the same. Fig. 9 is a side elevation shown partly broken away, of the lock applied to an automobile.

In said drawings, the reference numeral 10 designates the hand lever utilized in certain types of automobiles for holding the power transmission clutch in neutral and serving to actuate the brake shoes within the rear wheel drums.

According to the present invention, I provide a "combination" padlock, indicated generally by P in Fig. 9, which, as illustrated, is hingedly connected to the driver's seat so as to releasably engage said lever in the shackle of the lock for securing the lever in the position it will occupy when the mechanisms regulated thereby are regulated to render the vehicle inoperable.

Specifically, my improved lock comprises a casing 11 open at the top and pivotally connected at one end by a pin 12 to a hinge element 13 which is secured to the seat support 14 by rivets, or otherwise. Said casing is provided with a cover 15 which is detachably secured thereto by having one of its

ends engage under a lip 16 formed on the casing and having at its other end a downwardly directed flange 17 with an aperture to receive a screw 18 which engages in a threaded hole 18¹ provided in the end 19 of the casing.

In this casing end, 19, are provided guide sockets 20 and 21 for the legs of the lock bow or shackle 22, one of said legs being connected by a pivotal pin 23 with a rod 24 extending between guide lugs 15¹ depending from the cover 15.

The inner end of the rod 24 is formed or provided with a bill 25 adapted to engage against the peripheries of disks 26 and 27 or be entered into the respective notches 28 and 29 of the latter, according to the relative rotary positions of the same.

More particularly, the disk 26 is rotatably mounted on a boss 30 provided in the casing and the other disk 27 is secured to an operating post 31 rotatable in bearings 32 and 32¹ respectively provided in the boss 30 and in the casing cover 15.

33 represents a stud detachably secured in any one of a number of holes 34, Fig. 8, provided in the periphery of the disk 26 and engageable by a hook-shaped finger 35 extending from the periphery of the disk 27 so that by turning the latter, through the agency of the post 31, the disk 26 may also be rotated.

On the cover is provided a dial 36 having graduation marks disposed so that the revoluble position of the finger 35 may be indicated through the medium of a pointer 37 provided on the post 31.

In operation, the post 31 is manipulated to first turn the disk 27 in one direction so that the finger 35 thereof will serve through its engagement with the stud 33 to turn the disk 26 to present the notch 28 in position to receive the bill 25 of the shackle rod connection 24. Said post is then turned in the opposite direction to move the disk 27 to have its notch 29 brought into coincidence with the notch 28 to allow the bill 25 to enter both notches. The shackle may then be withdrawn from the casing; the operator thereupon swinging the shackle to one side, as indicated by broken lines α in Fig. 3, for engaging about or disengaging from the hand lever 10.

To render the lock operative, the shackle legs are pushed into the casing sockets sufficiently to disengage the rod 24 from the disk

notches, the disks being thereupon disarranged by turning the post 31 in either direction.

The combination of the lock may be altered after removing the cover 15 from the casing by changing the stud 33 from one of the holes 34 to another by positioning the disk 26 so that its notch will accommodate the rod bill 25 and noting the position which the other disk will assume, as indicated by the pointer 37 with reference to the dial marks after the cover is replaced.

The cover can only be removed after withdrawing screw 18 and, in consequence of the screw being located whereat it is masked by the hand lever 10 when the lock is engaged, it is apparent that the combination cannot be changed when the lock is employed, nor the operative parts otherwise tampered with.

What I claim is—

1. In a locking device for automobiles, the combination with a lever thereof, of a shackle engageable with said lever, a casing into which said shackle extends, combination lock elements provided in said casing for securing said shackle in operative posi-

tion, means to regulate said elements to render them operative or inoperative to secure said shackle, said casing having a removable cover, and means for detachably connecting said cover to the casing and located so that the cover can not be removed from the casing to enable said lock elements to be regulated when the shackle is engaged with said lever.

2. In combination with a fixed support and a lever, of a casing hingedly connected to said support, a shackle engageable with said lever, a rod hingedly connected to said shackle and extending into said casing, combination lock elements provided in the casing and engageable with said rod for releasably securing the shackle in its engaged position with respect to said lever, a cover for said casing, and means guarded by said lever when engaged by the shackle for detachably connecting said cover to the casing.

Signed at Seattle, Wash., this 18th day of Sept. 1917.

JOHN H. CORNALL.
